UNITED STATES PATENT OFFICE.

JOHN F. PARKES, OF NORTH TONAWANDA, NEW YORK, ASSIGNOR OF ONE-HALF TO CALEB W. WATKINS, OF SAME PLACE.

TOOL-HOLDER.

SPECIFICATION forming part of Letters Patent No. 291,531, dated January 8, 1884.

Application filed April 23, 1883. (No model.)

To all whom it may concern:

Be it known that I, JOHN F. PARKES, of North Tonawanda, in the county of Niagara and State of New York, have invented new and useful Improvements in Tool-Holders, of which the following is a specification.

This invention relates to certain improvements in the construction of cutter-heads for planing-machines, and more particularly to 10 that class of cutter-heads which are provided with longitudinal grooves in which the bolts engage, whereby the planing-knives are secured to the cutter-head. These grooves vary in width in different cutter-heads; and my invention has for its object to construct a tool-holder for a beading-tool or other auxiliary tool, which can be readily applied to a cutter-head and adjusted to fit in the groove with which the same is provided.

20 My invention consists of the improvements which will be hereinafter fully set forth, and pointed out in the claims.

In the accompanying drawings, Figure 1 is a fragmentary side elevation, and Fig. 2, an end elevation, of a cutter-head provided with 25 my improvements. Fig. 3 is a perspective view of the tool-holder. Fig. 4 is a sectional elevation of the same. Fig. 5 is an inside elevation of the tool-holder, illustrating a modified construction of the same.

30 Like letters of reference refer to like parts in the several figures.

A represents the cutter-head of a planing-machine, provided in two or more of its sides 35 or face with undercut longitudinal grooves *a*, which are adapted to receive the heads of the bolts, whereby the planing-knives are secured to the cutter-head.

B represents the beading-tool, and C the 40 tool-holder, in which each beading-tool is secured. The tool-holder C is composed of a socket portion, *d*, provided with a groove, *e*, in which the beading-tool is secured by a set-screw, *f*. The socket *e* is provided on one 45 side with an extension or ear, *g*, which overlaps the groove *a* in the cutter-head, and is provided with an opening, *h*, through which passes a fastening-bolt, *i*. The latter has its head *i'* arranged in the undercut groove *a* of 50 the cutter-head, and is provided at its outer end with a screw-nut, *i''*, which bears against

the outer side of the ear *g*, whereby the tool-holder is firmly secured to the cutter-head. The socket *d* is provided on its inner or rear side with a web or rib, *j*, which projects into 55 the narrow portion *a'* of the undercut groove *a*, as clearly represented in Fig. 2. The web *j* is made narrower than the narrow portion *a'* of the groove *a*, and the play of the rib *j* in said portion of the groove is taken up by 60 set-screws *k*, which are tapped into the side of the rib *j*. The set-screws *k* are arranged on the forward side of the rib *j*, so that the pressure of the beading-tool is received by the back of the rib *j* resting against the solid portion of 65 the cutter-head, while the set-screws *k* are relieved from pressure, and serve merely as guides to fit the rib in the groove. By adjusting the set-screws *k* the rib *j* can be adapted to fit snugly in grooves varying in width. 70

As represented in Fig. 5, the rib *j* may be made wedge-shaped and provided with an adjustable wedge-shaped piece, *l*, applied to one side of the rib *j*, so that by adjusting the piece *l* lengthwise on the rigid rib *j* the aggregate width of the web formed by the pieces *j* and *l* can be increased or reduced to correspond with the width of the groove in which the tool-holder is to be secured. 75

The adjustable wedge *l* may be secured to 80 the rib *j* by a set-screw, *m*, which is tapped into the rib *j*, and which passes through an elongated hole, *n*, in the wedge *l*, so that upon loosening the screw the wedge *l* can be adjusted, and after adjustment can be tightened by 85 means of the screw *n* in an obvious manner.

The pieces *j* and *l* may be provided on their adjacent inclined faces with a longitudinal rib formed on one part and projecting into a groove in the other part, to retain the parts 90 in their proper relative position, and prevent the movable piece from turning on the screw in adjusting the same.

The end portion of the extension *g* is provided with a raised edge, *g'*, adjacent to the 95 cutter-head, whereby the pressure in tightening the bolt *i* is thrown upon the raised edge *g'* and the beading-tool *B*, thereby clamping the latter securely against the cutter-head.

I claim as my invention— 100
1. The combination, with a cutter-head having a groove, *a'*, for securing a tool-holder

thereto, of a tool-holder provided with a rib, *j*, projecting into said groove, and adjusting mechanism applied to the side of said rib, substantially as described, whereby the width of said rib can be adjusted to correspond with the width of said groove, substantially as set forth.

2. The combination, with a cutter-head having a groove, *a'*, for securing a tool-holder thereto, of a tool-holder provided with a rib, *j*, projecting into said groove, and adjusting-screws *k*, applied to the side of said rib in said

groove, for adjusting the width of the rib to fit in the groove, substantially as set forth.

3. The combination, with a cutter-head provided with a longitudinal groove, of a tool-holder composed of a socket portion, *d*, having a groove, *e*, and an extension, *g*, having a bolt-hole, *h*, and a raised edge, *g'*, substantially as set forth. 15

JOHN F. PARKES.
